DEGREASING

Max Y. Seaton, Greenwich, Conn., assignor to
Westvaco Chlorine Products Corporation, New
York, N. Y., a corporation of Delaware

Application April 2, 1940, Serial No. 327,541

5 Claims. (Cl. 202—56)

This invention or discovery relates to degreas-
ing; and it comprises, in a method of vapor-
phase degreasing by a body of organic solvent
vapor established and maintained as a layer be-
tween a supply of boiling solvent and a super-
natant atmospheric layer, with metal parts or
other objects to be degreased being brought into
contact with said body of solvent vapor, and with
solvent vapor taken from a high level in said
layer being condensed and returned, the improve-
ment wherein water is removed from the system
by contacting the vapor in said body, or the con-
dense formed therefrom, with a drying agent
adapted to take up the water, advantageously by
absorption; and it comprises apparatus adapted
for application in the practice of this process;
all as more fully hereinafter set forth and as
claimed.

Vapor-phase degreasing systems are well-
known and widely employed for the removal of
grease, dirt, etc., from various types of metal
objects. In some instances, metal sheets and
other large objects are subjected to a degreasing
treatment of this type, and in other instances,
nuts, bolts and other small machine elements are
so treated, usually in baskets or racks adapted to
hold a large number of these small pieces.

Generally speaking, a vapor-phase degreaser
includes a reservoir for solvent, means for heating
the solvent in the reservoir and evaporating
it therefrom, and a chamber above the reservoir.
The chamber holds a body of solvent vapors
evolved from the solvent in the reservoir, and is
generally provided with a cooling coil or other
cooling means positioned at an appropriate
height in the chamber, and adapted to prevent
the vapors from rising too far, or passing into
the air and out of the system. The degreaser is
also provided with suitable means for conducting
the articles to be degreased to, through and from
the vapor chamber. This may include a suitable
trolley system with baskets or racks for small
parts to be treated.

Any volatile grease solvent yielding relatively
heavy vapors—that is, vapors of comparatively
high molecular weight—can be used. In practice, halogenated derivatives of the aliphatic hy-
drocarbons, such as trichlorethylene, are partic-
ularly favored as solvents. They are substan-
tially free from the fire hazard which accom-
panies the use of volatile hydrocarbons.

In operation of a degreasing system, solvent in
the reservoir is boiled, usually by passing steam

at suitable pressure through heating coils in the
reservoir. Solvent vapors are evolved and pass
upwardly into the degreasing chamber where,
being considerably heavier than the atmosphere,
they tend to form a more or less uniform layer
or lake. At or near the desired upper surface
of this vapor layer or lake, cooling coils are pro-
vided on the sides of the chamber, and these
coils are maintained at such temperature that
any solvent vapors reaching them are condensed.
The condensed vapors of clean solvent are ordi-
narily collected in an annular trough or channel
extending around the chamber below the cool-
ing coils, and from this trough, the condensate
is returned to the system. It is generally re-
turned to a clean solvent reservoir, separate from,
but communicating with, the evaporating reser-
voir. In some methods of operation, the articles
to be degreased are dipped into the solvent reser-
voir before being held in contact with the solvent
vapors.

As stated, the solvent vapors tend to form a
substantially uniform layer between the boiling
solvent and the supernatant atmospheric layer, 25
because of their high specific gravity. In opera-
tion there is, of course, an intermediate layer
between the solvent vapor and the normal at-
mosphere, in which a certain amount of solvent
vapor is mixed with air due to disturbances
caused by introducing articles to be degreased
into the vapor lake and removing them there-
from. This intermediate layer generally does
not extend substantially above the cooling coils,
however, because the solvent content of such a
layer, when proper solvents are employed, is
readily condensed. It is generally desirable to so
regulate the steam supply to the evaporating
section that a minimum amount of solvent is
condensed by the cooling coils. Condensation of
excessive amounts of solvent vapor involves a
waste of both steam and cooling water. In order
to maintain a body of solvent vapor of the desired
depth, however, it is necessary to supply a cer-
tain excess of heat units and to condense a cer-
tain amount of solvent on the coils.

When a vapor-phase degreasing system is in
operation, articles more or less coated with grease
and other dirt are immersed in the solvent vapor
in any suitable manner. Due to the relatively
low temperature of the "work" or treated mate-
rial, the solvent vapor condenses on its surface;
and the condensed solvent then drips off, carry-
ing with it the grease and other dirt and impuri- 55

ties. These tend to accumulate in the solvent evaporating section, being generally less volatile than the solvent.

The solvent employed is generally anhydrous or commercially dry when it is introduced into the system, but under some climatic conditions water enters the system by condensation from the atmosphere. Water is also introduced with the articles which are degreased. The presence of water in degreasing systems is highly undesirable for a number of reasons. For example, it tends to cause decomposition and acid formation in the chlorinated solvents which are most desirable for use in such systems; and this effect of moisture is aggravated by the high solvent temperatures which are maintained in degreasing operations. Trichlorethylene is not affected so much by water as some of the other chlorinated hydrocarbons, and is widely used in vapor-phase degreasers. However, cheaper solvents, such as carbon tetrachloride, for example, can be employed to advantage in degreasing systems if water is excluded from the system or promptly removed therefrom before it has an opportunity to cause solvent deterioration and metal corrosion. The exclusion or prompt removal of water is also advantageous in improving the effectiveness of a degreasing system, and the uniformity of its operation with any solvent.

30 In my copending application, Serial No. 220,378, of which the present application is a continuation-in-part, I have disclosed that the difficulties encountered because of the entrance of moisture into a vapor-phase degreasing system can be avoided by providing in the system means for contacting the solvent vapors, or the condensate formed therefrom, or both, with suitable inorganic adsorbents, such as calcined magnesia, activated alumina, activated bauxite, silica gel, activated magnesia and like materials. I have also disclosed in the said application that by properly selecting these adsorbents, any acids which are formed in the system can be eliminated, and that the odoriferous substances formed from the greases and other impurities collected in the system during operation can also be eliminated.

In many instances, it is highly desirable to eliminate two or more of these undesired materials (water, acids and odoriferous bodies) ordinarily encountered in vapor-phase degreasing systems, and this is readily accomplished in accordance with my said prior application. However, there are many other instances in which it is only necessary or desirable to eliminate the moisture. In such circumstances, I have found that highly desirable and beneficial results are obtained by the application of hygroscopic agents which do not have substantial adsorbent properties. Useful substantially non-adsorbent inorganic materials for this purpose include calcium chloride, magnesium perchlorate, P_2O_5 , specially baked calcium sulfate, caustic soda (either in the anhydrous or monohydrated form), lime, and numerous other known desiccating or dehydrating agents. For the sake of convenience, materials of this type are generically designated herein as non-adsorbent inorganic drying agents. It should be understood, however, that some of these materials may have some adsorbent properties; but that the dehydration resulting from the use of such compounds depends more on absorption or chemical combination of the water than on adsorption. In many instances, the water taken up by the drying agents now contemplated causes liquefaction or solution of these agents.

The non-adsorbent inorganic drying agents which I employ to eliminate water may be used, if desired, in conjunction with adsorbent materials which have the function of eliminating acids or odoriferous substances from degreasing systems. Ordinarily, however, I prefer to use these dehydrating agents alone. It should be understood that several of the useful non-adsorbent drying agents contemplated in the present invention have an alkaline reaction, this being true of caustic soda, lime, etc.; and such dehydrating agents serve to neutralize acids present in the system, while removing moisture therefrom.

After the drying agent to be employed in accordance with this invention is selected, it may be applied in various ways, as with the adsorbent materials described in my aforesaid prior application. For example, a basket of perforated metal or wire screen containing lime or other dehydrating agent is suspended in the body or stratum of solvent vapor in the degreasers, and any vapor coming in contact with this dehydrating agent is substantially freed from moisture. I find that it is generally even more effective, however, to provide a container of the selected drying agent in the path of the liquid condensed solvent returning from the cooling coils to the degreaser reservoir. As previously stated, the usual vapor-phase degreaser includes an annular channel or gutter which collects the condensed solvent dropping from the cooling coils. With such an arrangement, it is a simple matter to introduce a percolating tower containing lime or caustic soda or calcium chloride or other selected dehydrating agent into the line which returns the clean condensed solvent from this collecting channel to the clean solvent well, or to any other desired part of the system. If desired, part of the condensed solvent may flow through this tower in contact with the dehydrating agent, while part of it is by-passed around the tower directly back to the reservoir.

If desired, a non-adsorbent drying agent may be employed in a percolating tower through which the recondensed solvent passes, and in which it is dehydrated, and a suitable adsorbent may be simultaneously employed in contact with the solvent vapors to remove odoriferous substances, etc., therefrom.

In order that my invention may be more readily understood, it will now be described with reference to the accompanying drawing, in which the single figure is a somewhat diagrammatic illustration of a cross sectional view of a vapor phase degreasing apparatus adapted for operation in accordance with my invention.

In the drawing, the walls or shell 2 enclose a degreaser having a bottom portion which is divided into a vaporizing section or evaporator 4 and a clean solvent well 6. The vaporizing section 4 is provided with steam coils 8 which are supplied with steam from any suitable source (not shown) in quantity sufficient to vaporize the desired amount of solvent. The vaporized solvent rises into the chamber above the vaporizing section to a predetermined level, such as that indicated by the line 9, and any substantial quantity of vapor rising above this level is condensed by the cooling coils 12. These coils are advantageously individually controlled, so that effective cooling can be accomplished at any desired level. Condensate formed by the operation of the cooling coils collects in the annular channel 14, from which it may be returned to any desired part of the system, such as the clean solvent well 6,

through a pipe 16, for example. This pipe 16 may be provided with an adjustable level regulator and a valve 18; or the pipe may be omitted, in which case condensed solvent overflows from the trough 14 into the well 6.

5 In one embodiment of my invention, a wire screen or perforated metal basket 20 containing a granular drying agent or adsorbent, or both, is suspended in the vapor stratum, and the desired 10 purification of the solvent vapor is effected by removal therefrom of water or acids, or odoriferous substances, or a plurality of these undesired constituents, depending on the contents of the said basket.

15 In another and generally more advantageous embodiment of my invention, the condensate collected in the channel or gutter 14 passes through a suitable conduit 22, which is advantageously controlled by valve 23, into a percolating tower 24 or other suitable vessel. This tower or container is advantageously provided with a removable cap or cover 26, and a removable basket of perforated metal or wire screen 28 fitted rather snugly in its interior. This basket is 20 filled with a suitable drying agent such as lime or caustic soda or calcium chloride, advantageously in granular form, through which condensate delivered through the passage 22 must trickle or percolate on its way back to the system. This results in an effective drying of the 25 condensed solvent, which then flows through a pipe 30 back to the clean solvent reservoir 6. Part of the condensed solvent may be by-passed around the percolating tower, as by flowing directly from the collecting channel 14 back to 30 the clean solvent reservoir 6 through the pipe 16, if desired. In this procedure, the valve 18 and the pipe 16 are adjusted to maintain the desired level in the channel 14. Alternatively, the valve 35 18 may be closed entirely.

If desired, I may, as previously stated, employ both the external percolating tower 24 and the internal suspended basket 20; and the two containers may be filled with similar drying agents, 40 or one may contain a drying agent while the other contains an adsorbent. It is seldom neces-

sary or desirable to employ both of these excipients simultaneously, however.

Clean solvent collected in the reservoir 6 overflows into the evaporating section 4, from which it is again vaporized into the degreasing chamber. I have found that in all the embodiments 5 of my invention water is readily eliminated from the system when employing suitable drying agents of the type mentioned hereinabove; and acids and odoriferous substances may also be eliminated or minimized if desired.

10 My invention has been described hereinabove with special reference to certain types of construction, methods of operation, and choices of dehydrating agents which are now considered 15 desirable, but it is to be understood that these references are made by way of illustration only, and that the invention is not limited to them, but may be variously embodied and practiced within the scope of the appended claims.

20 What I claim is:

1. In a process of vapor-phase degreasing, wherein a body of organic solvent vapor of high molecular weight is established and maintained between an underlying boiling body of the liquid 25 solvent, and a supernatant atmospheric layer, with cooling and condensation of solvent vapor passing upwardly above a pre-determined level in said body of vapor, and return of condensed solvent to the system, the improvement comprising 30 contacting solvent vaporized from said boiling body of solvent and before its return thereto with a drying agent to remove water therefrom.

2. The process of claim 1, wherein said drying agent is a substantially non-adsorbent in- 35 organic material.

3. The process of claim 1, wherein the said drying agent is contacted with vaporized solvent in said body of solvent vapor.

4. The process of claim 1, wherein the said drying agent is contacted with solvent after said condensation thereof.

5. The process of claim 1, wherein said drying agent comprises material having an alkaline reaction which neutralizes acidity in the said solvent.

MAX Y. SEATON.
